CLAIM

The ornamental design for a golf putting green cup, as shown and described.

DESCRIPTION

FIG. 1 is a perspective view of a golf putting green cup, showing my new design;

FIG. 2 is a right-side elevation view of the golf putting green cup of FIG. 1;

FIG. 3 is a left-side elevation view of the golf putting green cup of FIG. 1;

FIG. 4 is a rear plan view of the golf putting green cup of FIG. 1;

FIG. 5 is a front plan view of the golf putting green cup of FIG. 1;

FIG. 6 is a top elevation view of the golf putting green cup of FIG. 1; and,

FIG. 7 is a bottom elevation view of the golf putting green cup of FIG. 1.

The broken lines show portions of the golf putting green cup that form no part of the claimed design.
